RACK FOR WARP TYING MACHINES

Hugh P. Eanes, Waterbury, Conn.

Application July 13, 1934, Serial No. 735,038

10 Claims. (Cl. 28—41)

My invention relates to an improvement in a rack for warp tying machines.

The purpose of my invention is to provide a rack for holding two layers of warp threads in a position to be picked up by a knot tying machine, such as the one disclosed in an application filed by me on even date, Ser. No. 735,037.

A further object of this invention is to provide a rack on which the warp threads can be easily placed and adjusted in proper position.

In the accompanying drawings,

Fig. 1 is a plan view;

Fig. 2 is a side elevation;

Fig. 3 is a cross section, on the line 3—3, of Fig. 2;

Fig. 4 is an enlarged cross-section of one thread holding bar; and

Fig. 5 is a perspective of a locking ring.

The frame 2 is mounted on any suitable carriage, and is provided on its upper edge with the tracks 4, on which the tying machine (not shown) rides.

The uprights 6 are secured to the frame 2 in a suitable manner, such as by means of the brackets 8, and the adjustable collars 10. On the upper ends of these uprights 6, I provide on one side of the rack, the bar 12 which is U-shape in cross section, as shown in Fig. 3. The bar 14 which is similar to the bar 12 is secured to an arm 16 by means of the bracket 18, and is placed along side the bar 12 and held there by the bracket 20 which is secured to the uprights 6 by means of a screw or bolt.

The bottom of the channels within the bars 12 and 14 are covered with rubber strips 22, on which the rods 24 rest when placed within the channels.

On the other side of the machine I utilize cylindrical bars 26 and 28, which are channeled similarly to the bars 12 and 14, which channels 40 are lined with rubber strips 22' on which the rods 24' rest when placed in position.

When it is desirable to place the warp threads on this rack, the arm 16 carrying the bracket 18 and the bar 14 is swung upwardly on the bar 28 as a pivot point and removed entirely from the top of the rack as shown in the dotted lines of Fig. 3.

When this portion of the rack is removed and has assumed the position shown in dotted lines 50 in Fig. 3, the rods 24 and 24' are removed from the bars 12 and 26. When this is done, the warp threads 30 are placed first over the bar 12 and secured in their proper position by means of the rod 24. After the threads 30 are secured to the 55 bar 12 they are combed across the rack and are

secured to the cylindrical bar 26, by means of the bar 24' which is then locked into position by means of the locking ring 32.

After this set of warp threads has been secured in proper position on the bar 12 and the cylindrical bar 26, the arm 16 with its bracket 18 and the bar 14 are swung back into position as shown in Figs. 1 and 3, and the warp threads 34 are properly positioned on the bar 14 and the cylindrical bar 28, in the same manner as described above.

The cylindrical bars 26 and 28 are provided at their ends with knurled nuts 36 and 38 respectively, at one end thereof, and with the knurled handles 40 and 42, at the other end thereof.

By holding the handle 40 and turning the cylindrical bar 26, any desired tension may be placed on the warp threads 30 after which the knurled nut 36 is tightened to secure the bar 26 in its adjusted position. The bar 28 may be similarly adjusted by turning the handle 42 and securing the cylindrical bar 28 in position by tightening the knurled nut 38.

The upper sides of the bar 12 and the cylindrical bar 26 are arranged in a horizontal plane, and the upper edges of the bar 14 and cylindrical bar 28, are arranged in a slightly higher horizontal plane than the upper surfaces of the bars 12 and 26, so that the warp threads 30 and 34 will be spaced apart slightly, as shown in Fig. 3.

The locking rings 32 are mounted on the cylindrical bars 26 and 28 at opposite ends thereof, so that after the rods 24' have been forced down within the channels of the bars 26 and 28 they may be securely held there by turning the locking ring 32, so it will assume a position shown in Fig. 3. The ends of the rods 24' away from the locking ring 32 are held down within the channels in the bars 26 and 28 by means of a projection 44 thereon which extends beneath the lip 46 of the bars 26 and 28 in the end of the channels, as shown in Fig. 2.

The bars 14 and 28 may be slid longitudinally of the frame 2 a short distance so that the warp threads 30 and 34 may be brought into perfect alignment. This adjustment is accomplished by means of a hand-wheel 48, which is secured to one end of a shaft 50 mounted on the frame 2 by means of suitable brackets 52. At the other end of the shaft 50, I provide a worm gear 54 which meshes with the gear 56 mounted on a cross-shaft 58 in the end of the frame 2.

The rod 60 extends upwardly from the shaft 58 at a convenient point approximately in the

center of the frame 2 and projects through an ear 62 on the arm 16. By turning the hand-wheel 48 and the shaft 50, the worm gear 54 is turned and consequently the shaft 58, which in turn moves the upright rod 60 either backward or forward, and thus moves the bars 14 and 28 longitudinally of the bars 12 and 26 to effect an adjustment between the warp threads 30 and 34 which are positioned on the bars 12 and 26, and 14 and 28, respectively.

In Fig. 4 I have shown more in detail the manner in which the warp thread 30 is secured by means of the rubber strip 22' and the rod 24' to the bar 26.

15 I have found that by utilizing this particular rack for a tying-in machine, that the machine operates more successfully by reason of the fact that the warp threads of the upper and lower bank may be continually held in proper alignment with one another while they are also held under proper tension. The result is that the warp threads when thus held are more readily picked up by the selector head of the tying machine and less errors are made, such as the selection of only 20 one thread or more than two threads.

25 While I have only shown a small number of warp threads 30 and 34, it will be understood that while the device is in use the entire length of the bars 12, 14, 26 and 28 will be filled with warp 30 threads which will be held in proper position and condition to be picked up and tied together by a tying machine. It will also be understood that there is no limit to the length of the bars 12, 14, 26, and 28. These bars may be made any 35 desirable length, their length being dependent on the width of the warps to be held and tied.

40 It will be understood that there may be slight changes made in the construction of this device, without departing from the spirit of the invention.

45 I claim:

1. In a rack for tying-in machines, a set of bars for holding warp threads, a set of similar bars disposed above the first named bars, and 50 means for moving said second set of bars longitudinally of the first-mentioned set of bars, said means consisting of a hand wheel, a worm gear, a shaft which is rotated by the rotation of the worm gear, and a rod secured perpendicularly to the shaft and movably to the said second set of bars.

55 2. In a rack for tying-in machines, a set of bars in spaced apart relation for holding warp threads, a set of bars in spaced apart relation arranged above the first-mentioned bars, and means for pivotally and laterally removing the said second set of bars from their position above the first-mentioned set of bars.

3. A rack for warp tying machines including 60 two sets of bars in spaced apart relation for holding warp threads, one set arranged above the other, and means for pivotally swinging one set of bars from their position above the other set of bars.

65 4. A rack for warp tying machines, including a frame, two sets of thread holding bars, one set slidable longitudinally of the other, a shaft extending transversely of the frame, a rod extending transversely of said shaft and connected

to one set of thread holding bars, and means for turning said shaft.

5. A rack for warp tying machines including two sets of thread holding bars, one set slidable longitudinally of the other, a shaft extending 5 transversely of a frame upon which said bars are mounted, a rod extending transversely of said shaft and connected with said slidable thread holding bars, and means for turning said shaft.

6. In a rack for tying-in machines, bars in 10 spaced-apart relation, rods frictionally engaging said bars for securing warp threads thereto, a second set of bars and rods spaced apart and positioned above said first-mentioned set of bars and rods, and means connected with one bar in 15 each set of bars for turning said bar to adjust the tension of the warp-threads held thereby.

7. In a rack for tying-in machines, a bar having a longitudinal groove therein, a rod adapted to frictionally engage said groove and secure warp 20 threads therein, a cylindrical bar having a similar groove and bar in spaced apart relation to and in the same horizontal plane with said bar, and means associated with said cylindrical bar for turning said bar and rod on its axis to effect an 25 adjustment of the tension of the threads held by said bars and rods.

8. In a warp-tying machine having a main supporting frame and two pairs of thread clamps for supporting respectively upper and lower series 30 of warp threads with the clamps of each pair disposed on opposite sides of said frame, a support pivotally mounted on said frame and carrying at least one of the clamps for supporting the upper series of threads, said support being swingable to carry said one clamp upwardly away from the corresponding clamp of the other pair and into an out-of-the-way position relative thereto.

9. In a warp-tying machine, the combination of an elongated supporting frame, and means for 40 supporting two series of warp threads in vertically spaced relation and in a position to be operated upon by a tying mechanism, said means including a stationary clamp mounted in a horizontal position at one side of said frame and a 45 second clamp pivotally mounted on said frame and swingable on a horizontal axis from a normal position parallel and adjacent to the stationary clamp into a position substantially removed from the stationary clamp.

10. In a warp-tying machine, the combination of an elongated supporting frame, and means for supporting two series of warp threads in vertically spaced relation and in a position to be operated upon by a tying mechanism, said means including two thread-holding clamps arranged in 55 parallel relation at one side of the frame and having thread-engaging surfaces disposed one above the other, a supporting arm having an upright end portion pivotally supported on the 60 frame and a horizontal portion overlying the frame and carrying the clamp having the uppermost thread-engaging surface, and a member carried by said frame for supporting the last-mentioned clamp in a horizontal position parallel 65 to the other clamp, said arm being swingable to carry the clamp thereon upwardly into an out-of-the-way position relative to said other clamp.

HUGH P. EANES.
